(57) CLAIM

I claim the ornamental design for weight with handles, as shown and described.

DESCRIPTION

FIG. 1 is a front elevational view of a weight with handles. FIG. 2 is a front, top and right side perspective view of the weight.

FIG. 3 is a front, top and left side perspective view of the weight; and,

FIG. 4 is a front, bottom and right side perspective view of the weight.

The broken lines in the drawing views is included to show unclaimed environment only and forms no part of the claimed design.

1 Claim, 4 Drawing SheetsFIG. 1

FIG. 4
